LEFT FOOT REST FOR AUTOMOBILE OPERATOR

George E. Bisanar, 431 6th St. NW,
Hickory, N.C. 28601

Filed June 2, 1966, Ser. No. 2,509

Term of patent 14 years

(Cl. D14—6)

FIGURE 1 is a perspective view of the left foot rest embodying my new design;

FIGURE 2 is an end elevation view of the left foot rest shown in FIGURE 1, taken from the left-hand end of the article as shown in FIGURE 1 and showing the end thereof remote from the end visible in FIGURE 1; and

FIGURE 3 is a perspective view of the left foot rest shown in FIGURE 1 wherein a dotted line showing a portion of an automobile has been included for illustrative purposes only in order to clarify the disclosure of my new design.

The side not shown is a mirror image of the side shown in FIGURES 1 and 3.

I claim:

The ornamental design for a left foot rest for automobile operator, as shown and described.
